MARBLE GAME BOARD

John Eisenhut, R.D. 5, Carrollton, Ohio

Filed Aug. 16, 1962, Ser. No. 71,315

Term of patent 14 years

(Cl. D34—5)

Fig. 1

Fig. 2

Fig. 3

FIGURE 1 is a plan view of a game board showing my new design;

FIG. 2 is an edge view thereof; and

FIG. 3 is an enlarged fragmentary vertical sectional view, taken on the line 3—3 of FIG. 1.

The characteristic feature of my design resides in the combination on my game board of a cruciform pattern of circular depressions having tear drop areas of contrasting color surrounding the peripheral cluster of depressions about said cruciform, and angular quarters of contrasting color on the board, all as shown.

I claim:

The ornamental design for a marble game board, substantially as shown and described.
